Des. 1204

P. S. Vedder, of Troy, New York, N.Y.

Assignor to

Abraham & Joseph Cox, and Jno. Whitteman.

Letters Patent No. 1204, dated Feb. 21, 1860.

The schedule referred to in these Letters Patent and making part of the same.

To all whom it may concern.

Be it known that I, P. S. Vedder, of Troy, Rensselaer County, State of New York, have invented or produced a new and original design for the plates of a Cooking Stove, termed the "William Penn", and I do hereby declare the following to be a full, clear and exact description of the same, reference being had to the accompanying drawing which forms a part of this specification, and in which -

Fig. 1. represents a side view of my design for a cooking stove.

Fig. 2. a front view,

Fig. 3. a plan view of the top plate -

Fig. 4, a full sized sectional view of the ornoulding on the edge of the bottom plate of the stove -

A represents the top plate of the stove B, one of the side plates, D, the bottom plate, E, E, the legs, F, the upper front plate, &, the lower front plate, and H, the ash pit plate.

The top plate A, is plain, is edged with a plain ornoulding a, and is of the form represented in Fig. 3.

The side plate has two oven doors b. and c, upper panels d. and e, and three lower panels f, f, f. -

The oven door b. is wider at the bottom than at the top, is edged with a plain ornoulding which incloses a waved ornoulding x, within which is a diamond shaped panel containing small diamond shaped projections as represented in Fig. 1.

The smaller door c. is edged with a moulding similar to that of the door b. and is ornamented with an inner waved moulding and diamond shaped projections of a similar character to those on the larger door.

The panel e. is ornamented by designs of a similar character to those on the doors b and c. but the panel d. is plain and edged with a plain ornoulding.

Each of the three lower panels f. contains an ornament consisting of a waved ornoulding which incloses diamond shaped projections and a row of sharp pointed ribs as illustrated in the drawings.

The bottom plate D, is plain, and edged with a moulding the form of which will be best observed on reference to the enlarged view Fig. 4.

Each leg E, has an ornamental cap, is edged with a curved moulding, and has diamond shaped projections in front, as shown in Figs. 1 and 2.

The ash pit plate H, is edged with a plain ornoulding as illustrated in the drawing, and the lower front plate &, has two doors on. on. ornamented with devices similar to those of the lower panels f. of the side plate B.

The upper front plate F, has two doors each having ornaments of a similar character to those on the smaller door c. of the side plate -

Above the door on the upper front plate is a panel edged with a plain moulding which incloses the title of the stove and above the latter a row of square orifices.

I claim, The combination of ornamental figures and forms represented in and by the accompanying drawing forming together an ornamental design for the plates of a cooking stove. -
